UNITED STATES PATENT OFFICE.

CADWALLADER M. RAYMOND, OF BOSTON, MASSACHUSETTS.

EXTENSION ICE-SKATE.

SPECIFICATION forming part of Letters Patent No. 357,629, dated February 15, 1887.

Application filed March 18, 1886. Serial No. 195,735. (No model.)

To all whom it may concern:

Be it known that I, CADWALLADER M. RAYMOND, a citizen of the United States, residing at Boston, in the county of Suffolk and State of Massachusetts, have invented a new and useful Improvement in Extension Ice-Skates, of which the following is a specification.

The object of my invention is to produce an ice-skate which can be readily adapted for feet of different sizes; and the invention consists in the combination, with an extensible foot-piece, of a blade so constructed as to enable the foot-piece to be adjusted to the blade to the required size of the foot.

Referring to the accompanying drawings, Figure 1 is a side view of my invention with the foot-piece in position when clamped to the foot. Fig. 2 is a transverse section through the skate and one of the hangers. Fig. 3 is a side view showing the position of the parts before the foot-plate is adjusted to the foot. Fig. 4 is a perspective view of a skate embodying my invention.

The main features of the foot-piece are similar to those described in Patent No. 313,622, granted to me for a roller-skate.

A and B are respectively the toe and heel plates, the toe-plate being bent at the point d, and having a slot through which the forward part of the heel-plate B passes, and thence through a recess in the upper part of the hanger P, secured to the toe-plate A. The toe-plate is passed in a similar manner under the heel-plate and through a recess in the upper part of the rear hanger.

At the rear of the heel-plate are the clamps b b, forming a portion of the heel-plate, and are bent upward and over inwardly at the upper ends, so as to securely hold the heel of the boot or shoe in position.

In the heel-plate is an elongated slot, in which is fitted a slotted plate, H, which is bent up at the rear end and projects to the rear, as shown in Fig. 1, so as to clamp the front end of the boot or shoe heel. It is capable of being adjusted to the size of the heel, and is held in position by means of the screw G and nut I. The forward hanger, P, is adjusted in the slot p by means of a bent lever, C, pivoted in the narrow portion of the heel-plate, and also to a plate connected to the screw-bolt G, thus actuating the toe-plate, all as described and shown.

The toe-plate is provided with clamps a a, 55 as shown.

To the under side of the heel and toe plates B A are secured the hangers P and Q, the hanger P under the toe-plate inclining forward at the lower end, and the hanger Q under the heel-plate being vertical.

K is the skate-blade, and has at its forward end a longitudinal slot, p, and at its rear end three holes, q q q. The lower ends of the hangers P and Q are slotted, so as to straddle 65 and be fitted upon the upper edge of the blade K, as indicated in Fig. 2. The ends of the hangers are secured in the slot and holes in the blade by screws L, as shown. The holes q at the rear end of the skate-blade admit of 70 the skate being adapted to feet of different sizes. By securing the hanger Q in the forward hole, q, the skate is adapted to a foot of small size, and when secured in the central hole a size larger is obtained. When secured 75 in the rearmost hole, q', the skate can be fitted to a foot of still larger size.

I design making the skate-plate of different lengths—one to be adapted to varying sizes for young people, and the other to the varying 80 sizes of older persons.

The hangers, instead of being cast in one piece, may be made of two iron plates secured to the under side of the foot-piece and passed down on each side of the skate-plate.

The holes may be made at the front end of the skate and the slot at the rear, and holes may be made in place of the slot.

What I claim as my invention is—

1. The combination of the extensible toe 90 and heel plates A B, the lever C and its connections, the hanger P, and blade K, provided with the slot p, as and for the purpose set forth.

2. In combination, the toe and heel plates 95 A B, the lever C and its connections, the hanger P, adjustable in the slot p, the hanger Q, adjustably connected with the skate-blade K, and the slotted and perforated skate-blade K, substantially as and for the purpose set 100 forth.

In testimony whereof I have signed my name to this specification in the presence of two subscribing witnesses.

C. M. RAYMOND.
